(75) Inventor: **Thomas A. Whorley**, Mineral Springs, TX (US)

* cited by examiner

(73) Assignee: **Cantex, Inc.**, Mineral Wells, TX (US)

Primary Examiner—Joel Sincavage

(**) Term: **14 Years**

(74) Attorney, Agent, or Firm—Miles & Stockbridge PC; Edward J. Kondracki

(21) Appl. No.: **29/190,413**

(57) **CLAIM**

(22) Filed: **Sep. 22, 2003**

The ornamental design for a quick set device for mounting electrical devices, as shown and described.

(51) LOC (7) Cl. **13-03**

DESCRIPTION

(52) U.S. Cl. **D13/154**

FIG. 1 is a left side view of the design for a quick set device for mounting electrical devices.

(58) Field of Search **D13/154; 174/53, 174/58; 248/228.1, 906; 220/3.2, 3.9; 411/437**

FIG. 2 is a right side view of the design for a quick set device for mounting electrical devices.

(56) **References Cited**

FIG. 3 is a rear view of the design for a quick set device for mounting electrical devices.

U.S. PATENT DOCUMENTS

FIG. 4 is a top view of the design for a quick set device for mounting electrical devices.
